UNITED STATES PATENT OFFICE.

HENRY L. LEILICH, OF DELPHOS, OHIO, ASSIGNOR TO THE DELPHOS MANUFACTURING COMPANY, OF DELPHOS, OHIO, A CORPORATION OF OHIO.

WELL-BUCKET.

1,114,776.

Specification of Letters Patent. Patented Oct. 27, 1914.

Application filed August 25, 1913. Serial No. 786,487.

To all whom it may concern:

Be it known that I, HENRY L. LEILICH, a citizen of the United States, and a resident of Delphos, in the county of Allen and State of Ohio, have invented a certain new and useful Well-Bucket; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to well buckets of the valved bottom type, and has for its object the provision of an improved bucket of this character.

The invention is fully described in the following specification, and while, in its broader aspect, it is capable of embodiment in numerous forms, a preferred embodiment thereof is illustrated in the accompanying drawings, in which,—

Figure 1 is a side elevation of a bucket embodying the invention, Fig. 2 is an enlarged longitudinal section of the lower end portion thereof, and Fig. 3 is an enlarged perspective view of the lower end portion of the bucket with a part broken away.

Referring to the drawings, 1 designates the cylindrical body of a bucket, and 2 and 3 the upper and lower end portions thereof in preferably tapered form. Each of the end portions 2—3 is telescoped over the respective end of the body 1 and secured in a water tight manner thereto as by soldering, and the inner end of each of said end portions is provided with an integral outwardly projecting annular bead 4, which prevents the bucket from having contact with the side of the well casing except at the points 4 when being raised and lowered therein. The beads 4 are disposed entirely over the respective ends of the bucket body so that the bucket is reinforced at the point of sliding contact of the same with a well casing, thus preventing a leakage should the material forming the beads 4 become worn through.

The bottom 5 of the bucket is secured to and projects inwardly in frusto-conical form

from the lower edge of the end portion 3, and has its inner or frustum end open with its edge rolled outwardly to provide a seat 55 for a gravity valve 6. The valve 6 is intended to seat flat against the inner edge of the bottom 5, and has a bail member 7 projecting downward therefrom through the bottom opening and loosely around a cross-bar 8, which extends across the bottom 5, thus permitting the valve to have limited opening movements. The bar 8 extends across the conical portion of the bottom within the lower edge thereof and has its 65 ends projected into openings 9, which are provided therefor in the bottom at opposite sides thereof.

The upper end of the bucket is open and provided with a bail member 10, which is 70 secured at its ends to the upper end portion 2.

It is found in practice that a bucket of this form is strong and durable in its construction and capable of a long period of 75 use without wearing out, and also that the provision of an inwardly projecting conical form of bottom with a valve disposed within the same and normally closing the opening therein is an important feature, as the filling 80 of the bucket upon a lowering of the same into a well is more rapidly accomplished than would otherwise be the case, as the water within the confines of the outer edge of the bottom is forced upward into the 85 bucket through the restricted bottom opening when the bucket is lowered in the water. This form of bottom also enables the bucket to rest flat at its lower end upon a subjacent support as the placing of the cross-bar 90 8 within the hollow of the bottom permits the valve bail 7 to be forced upward above the lower edge of the bucket.

I wish it understood that my invention is not limited to any specific construction or 95 arrangement of the parts except in so far as such limitations are specified in the claim.

Having thus described my invention, what I claim as new and desire to secure by Letters Patent, is,—

A well bucket comprising a body of cylindrical form and tapered end portions secured to the opposite ends of the body, said end portions telescoping over the body ends

and having their telescoping portions externally beaded in annular concavo-convex form with the opposite edges of both of said beads in bearing contact with the body and with the protuberant portions of the beads forming protuberant bearing surfaces which are spaced from the body.

In testimony whereof I have hereunto signed my name to this specification in the presence of two subscribing witnesses.

HENRY L. LEILICH.
